UNITED STATES PATENT OFFICE.

WILLIAM H. MCKISSICK, OF TULSA, OKLAHOMA.

DRAINAGE-VALVE FOR DEEP-WELL PUMPS.

1,314,070.

Specification of Letters Patent. Patented Aug. 26, 1919.

Application filed December 7, 1918. Serial No. 265,762.

To all whom it may concern:

Be it known that I, WILLIAM H. MCKISSICK, a citizen of the United States, residing at Tulsa, in the county of Tulsa and State 5 of Oklahoma, have invented certain new and useful Improvements in Drainage-Valves for Deep-Well Pumps, of which the following is a specification, reference being had to the accompanying drawings.

10 This invention relates to means for draining or bleeding the pump tubes of deep wells, as for instance, oil wells and particularly to the provision of a drainage valve and means for automatically opening the 15 drainage valve when the pump tube is raised to thereby permit the drainage of the pump tube.

The general object of this invention is to 20 provide a very simple and easily operated device to this end which includes a sliding member mounted upon the pump tube and frictionally engaging the well casing which is caused to move downward with the pump tube when the latter is inserted in the well 25 but which when the pump tube is raised will cause the opening of the drainage valve.

A further object is to provide a drainage valve which is also adapted to be used as 30 a check valve for admitting oil to the pump tube in the ordinary operation of the pump or permitting the inflow of oil to the oil tube when the pump tube is inserted in a well which is filled with oil to a point above the valve.

35 Other objects will appear in the course of the following description.

My invention is illustrated in the accompanying drawings, wherein:—

Figure 1 is a longitudinal sectional view 40 of a well casing, a pump tube therein, and my drainage devices applied thereto;

Fig. 2 is a large fragmentary section illustrating the drainage valve in its open position;

Fig. 3 is a vertical sectional view of a well casing and pump tube provided with another form of my device; and

Fig. 4 is a like view to Fig. 3 but showing the pump tube partially in section and 50 the valve raised.

Referring to these drawings, 10 designates the well casing which is of the usual character and 11 an upper section of the pump tube

which at its lower end usually carries a standing valve or may carry a pump at the 55 bottom of the tube. In deep wells it is often necessary to withdraw the pump tube in order to repair the pump or the standing valves and means should be provided for draining off the oil within the pump tube 60 which would otherwise be carried to the surface and lost.

To this end, in the form of my invention illustrated in Fig. 1, I dispose below the section 11 of the pump tube a section 12 65 which is connected to the section 11 by means of a coupling 13 of any suitable character, this coupling having a greater exterior diameter than the diameter of the pipes 11 and 12. Connected to the section 70 12 by a relatively thick coupling 14 is a lower tubular section 15. The pump, if one is used, may be connected to the lower end of this tubular section 15 or the standing valve may be located at the lower end of this sec- 75 tion.

The coupling 14, as before stated, is relatively thick and is formed with a longitudinally extending bore 16 closed at one end, as for instance by a plug 17, and in the opposite end of the bore there is screwed a sleeve 18. Slidingly mounted within this sleeve 18 and fitting it snugly is a hollow, longitudinally movable valve 19 having the form of a cylinder or small pipe section 85 80 which is open as at 20 at its upper end and as at 21 at its lower end. This valve or pipe section 19 is longitudinally shiftable through the sleeve 18 and has a length greater than that of the sleeve 18 so that when this valve 90 is disposed so that it extends above the upper end of the sleeve 18, the perforations 21 will be closed but when the valve is lowered so that its upper end is coincident with the upper end of the sleeve 18, the perforations 21 will be disposed beyond the lower 95 end of the sleeve 18.

Disposed within the lower end of the bore 16 is a coiled compression spring 22 which urges the globular valve 23 against the 100 lower open end of the tubular valve 19. Thus when the valve 19 is in its normal position, as illustrated in Fig. 1, passage through the tubular valve is prevented, but when the valve 19 is forced downward and the perforations 21 are disclosed then communica- 105

tion is had between the interior of the coupling 14 and the exterior of the pipe 12 through a port 24 and the perforations 21.

For the purpose of forcing this valve 19 downward and rendering it operative to drain the interior of the pump tubing, I mount upon the pump tubing section 12 below the collar 13 the spaced collars 25 and 26, these collars being loose upon the pump tubing 12. Attached to these collars and connecting them are a plurality of bowed springs 27 which are resiliently urged outward into frictional engagement with the interior of the well casing. Normally the collar 25 is disposed immediately beneath the coupling 13 and thus when the pump tube composed of the sections 11, 12 and 15 is forced downward through the casing, the collar 13 will force the friction device 20 downward with it. When, however, the pump tube is pulled upward so as to remove the pump tube from the casing, the springs 27 engaging the well casing prevent the upward movement of the collars 25 and 26.

Now when the upper end of the valve 19 strikes the under face of the collar 26 this valve 19 will be forced downward until it is opened and the oil within the pipe 11 drains 30 out through the port 24 and the ports or perforations 21 into the tubular valve 19 and out of this valve into the well. Thus as the pump tube is raised it is drained.

Preferably the valve 23 will have a ground 35 joint with the lower end of the sleeve 18 and the piston valve 19 will be open at its lower end and a ground joint will be secured between the valve 23 and the piston valve 19.

In Fig. 3, I show another form of this invention which operates in substantially the same manner. This form is particularly adapted to be used below the pump itself or below the standing valve of the pump tube. In this figure, 28 designates a lower section 45 of the pump tube and 29 a coupling providing a valve seat for a standing valve 30. Engaged by the coupling 29 and depending from it is a pipe section 31 which is provided with a pair of longitudinally extending slots 32. Disposed within the pipe section 31 is a T-shaped member 33, the cross bar of which extends through the slots 32. The shank of this T-shaped member 33 is disposed immediately beneath the ball valve 50 30 and if this T-shaped member be raised, relative to the ball valve, it will lift the ball valve from its seat.

For the purpose of automatically and relatively raising this T-shaped member 33 60 when the pump tube is raised to thereby drain the pump tube of oil, I mount upon the exterior of the pipe section 13 the collars 34 and 35 which have sliding engagement upon the pipe section 31. These collars are connected by the outwardly bowed springs 36

which bear frictionally against the well casing. Carried upon one of these collars is an L-shaped member 37 having an arm 38 which extends circumferentially around the pipe 31 and in a plane below the collar 34. 70

The operation of this device is as follows: When the pump tube is inserted in the well, the friction of the springs against the well casing will, of course, prevent any downward movement of the friction device until 75 such time as the collar 29 strikes the collar 34. When this occurs the collar 34 and the springs are forced downward. Now when the pump tube is withdrawn or when it is desired to drain the pipe, then on an upward 80 movement of the pump tube the springs 36 will hold the collars 34 and 35 from upward movement with the pump tube. Now when the arm 33^a of the T-shaped bolt 33 has been lifted above the L-shaped lug 38 then the 85 tubing 28 and 31 is turned to the right to cause the arm 33^a to hook over the L-shaped lug 38. Then the tubing sections 31 and 28 are lowered and as the T-shaped member 33 is held stationary by the lug 38 the valve 90 30 will be brought against the upper end of the member 33 and the valve will be raised and thus the liquid may be drained back into the well.

It will be seen that both of these devices 95 are of very simple construction and easily operated, that they involve no rotation of the pump rod and in the case of the mechanism illustrated in Figs. 3 and 4, only a slight rotation of the pump tube, and that 100 a relatively slight movement of the pump tube is sufficient to cause the opening of the valve.

While I have illustrated two forms of my invention which I believe to be particularly 105 practical and effective in use, yet I do not wish to be limited to these, as it is obvious that many changes might be made therein, without departing from the spirit of the invention as defined in the appended claims. 110

I claim:

1. The combination with a pump tube, of a normally closed drainage valve mounted in the pump tube, a friction device slidably mounted upon the pump tube and adapted 115 to engage a well casing in which the tube is inserted, means limiting the sliding movement of said friction device relatively upward on the pump tube, and means engaged by said friction device upon a relatively upward movement of the pump tube causing the opening of said valve.

2. The combination with a pump tube, of a drainage valve mounted in the pump tube, and means slidably mounted on the pump 125 tube adapted to frictionally engage a well casing, said means operatively engaging the drainage valve to unseat it when the pump tube is moved relative to said means, the pump tube having means thereon for caus- 130

- ing the downward movement of the said means upon the downward movement of the pump tube, but permitting an upward movement of the pump tube independent of said 5 means.
3. The combination with a pump tube, of a normally closed drainage valve mounted in the pump tube, a member slidably mounted upon the exterior of the pump tube and having outwardly urged resilient portions frictionally engageable with a wall of the well casing, means on the pump tube carrying said member downward when the pump tube is lowered but permitting the independent upward movement of the pump tube, said sliding member operatively engaging the valve to lift it when said sliding member is held from relative movement with the pump tube and the pump tube is shifted in a 10 predetermined direction.
4. The combination with a pump tube, of a drainage valve in the pump tube, a pair of spaced collars loosely surrounding the pump tube, outwardly bowed springs connecting said spaced collars and adapted to bear frictionally against a well casing, a member mounted upon the pump tube operatively engaging the uppermost of said collars to cause the downward movement of the collars and the springs with the pump tube, but permitting the free upward movement of the pump tube, and means actuated by one of said collars for shifting the valve to an open position when the pump tube is 15 moved relative to said collars.
5. The combination with a pump tube, of a drainage valve including a sleeve, a sliding drain pipe mounted in said sleeve and longer than the sleeve and having perforations at one end and open at its other end, a pair of collars mounted upon the pump tube for sliding movement, outwardly bowed springs connecting said collars and adapted to frictionally engage a well casing, a member mounted upon the pump tube and shiftable into engagement with the uppermost of said collars to thereby shift the collars downward with the pump tube but permit the upward movement of the pump tube 20 relative to the collars, the lower collar being disposed in the path of movement of the tubular valve whereby when the pump tube is lifted relative to the collars, the lowermost collar will strike the valve and shift it to an open position.
6. The combination with a pump tube, of a drainage valve including a sleeve, a sliding drain pipe mounted in said sleeve and longer than the sleeve and being open at its opposite ends and formed with perforations adjacent its lower end, the tubular member being longer than the sleeve, a spring actuated valve normally closing the lower open end of the tubular member, a 25 pair of collars mounted upon the pump tube for sliding movement, outwardly bowed springs connecting said collars and adapted to frictionally engage a well casing, a member mounted upon the pump tube and shiftable into engagement with the uppermost of said collars to thereby shift the collars downward with the pump tube but permit the upward movement of the pump tube relative to the collars, said valve being disposed in the path of movement of the tubular valve whereby when the pump tube is lifted relative to the collars, the lowermost collar will strike the valve and shift it to an open position.
7. The combination with a pump tube, of a drainage valve mounted upon said pump tube resiliently urged to a closed position, said valve being movable in a direction parallel to the pump tube, a collar loosely supported upon the pump tube for sliding movement and adapted to frictionally engage a well casing, said valve being disposed in the path of movement of the collar whereby to cause the opening of the valve when the collar and pump tube are moved in one direction relatively to each other and the collar operatively engages with the valve, and means on the pump tube for causing a movement of said collar downward with the pump tube but permitting an independent upward movement of the pump tube.
8. The combination with a pump tube, of a diametrically enlarged member mounted upon the pump tube and having a longitudinally extending bore exterior to the pump tube, said member being hollow and communicating with the pump tube and said bore, a longitudinally slidable drainage valve mounted in said member and resiliently urged to a closed position, said valve when in a closed position projecting upward out of said bore and beyond said member, and a friction device slidably mounted upon the pump tube and adapted to frictionally engage a well casing, said longitudinally movable valve being disposed in the path of movement of said friction device whereby when the pump tube is raised relative to the friction device the valve will be opened, the pump tube being provided with means for causing the coincident downward movement of the friction device and the pump tube but permitting the independent upward movement of the pump tube.
9. The combination with a pump tube, of an annular hollow member mounted upon the pump tube and communicating therewith and having a longitudinally extending bore disposed exteriorly to the pump tube but in communication with the interior of the member, a sleeve mounted in the upper end of the bore, a tubular valve mounted in and longer than the sleeve and longitudinally shiftable therethrough, the inner end 120

of the valve being open, a spring urging the valve upward to thereby cause the lower perforations to be closed by the sleeve, and a member slidably mounted upon the pump tube and having means for frictionally engaging the wall of a well casing, said member when the pump tube is raised relative to the member engaging the valve to open it, the pump tube being provided with means for causing the coincident downward move-

ment of said slidable member but permitting the independent upward movement of the pump tube and valve.

In testimony whereof I hereunto affix my signature in the presence of two witnesses. 15
